FLOW CONTROLLING MECHANISM

Roy E. Warren, Houston, Tex.

Application February 1, 1932, Serial No. 590,179

1 Claim. (Cl. 251—134)

This invention relates to a flow controlling mechanism.

An object of the invention is to provide a mechanism of the character described for controlling the inflow of water, particularly into a boiler.

Another object of the invention is to provide in a mechanism of the character described a novel type of valve employed.

Another object of the invention is to provide novel means for actuating the valve.

With the above and other objects in view, the invention has particular relation to certain novel features of construction, operation and arrangement of parts an example of which is given in this specification and illustrated in the accompanying drawing, wherein:—

Figure 1 shows a side view of the mechanism as mounted on a boiler and,

Figure 2 shows a sectional view of the valve.

In the drawing the numeral 1 designates a boiler or other container leading into the top of which there is a supply pipe 2 incorporated into which is the valve casing 3. The supply pipe 2 leads into one side of the valve casing and is connected to the top thereof by means of a suitable coupling 3'. Threaded into the inner end of this coupling there is an outwardly tapering valve seat 4 and in the casing there is a valve 5 having a tapering portion conforming in contour to and adapted to seat closely within said seat 4. This valve 5 has an external annular shoulder 5' adapted to abut the inner end of the seat to limit the seating movement of the valve. The valve 5 is fixed to the inner end of the stem 6 which works through a stuffing box 7 carried by the casing and whose outer end carries an adjustable abutment 8. A coil spring 9 surrounds said stem and is interposed between said abutment and stuffing box and normally tends to open the valve. There is a lever 10 pivotally mounted on the boiler and whose outer end has a pivotally sliding connection with the outer end of the stem 6, and whose other end is extended beyond the pivotal support of said lever. There is a float 11 adapted to ride on the water in the boiler 1 and which is attached to the free end of the arm

12. The other end of this arm is fixed on a shaft 13 which rotates in a bearing 14 in the side of the boiler and fixed to the outer end of said shaft 13 there is an arm 15 whose free end is connected to the extended end of the lever 10 by means of the link 16.

As the level of the water in the boiler rises the float 11 will rise with it, operating through the mechanism described to lift the valve 5 and to close the seat 4 to shut off the inflow of water, meanwhile placing the spring 9 under compression. Pressure in the casing 3 will tend to hold said valve closed.

As the water level is lowered in the boiler the float 11 will descend operating through the 15 mechanism described assisted by the spring 9 to open the valve 5, and to again admit water to the boiler.

The inner end of the valve 5 is tapered as in 17 so as to offer a minimum resistance to the water 20 in the casing 3 as the valve is moved to open position.

The drawing and description disclose what is considered to be a preferred form of the invention by way of illustration only, while the 25 broad principle of the invention will be defined by the appended claim.

What I claim is:

In flow controlling mechanism a valve casing having a valve chamber therein, a coupling 30 threaded into one end of the casing and whose outer end is inwardly thickened forming a stop, a detachable outwardly converging valve seat threaded into the coupling into abutting relation with said stop, a flow line entering the 35 side of the chamber and leading outwardly therefrom through said seat, a valve in said chamber having tapering ends, one of which is shaped to fit within said seat, said valve also having an annular external shoulder arranged to abut the 40 opposing end of the seat when the valve is closed, a valve stem attached to the other end of the valve, a stuffing box carried by the casing through which said stem works and yieldable means normally tending to hold the valve open.
